Attorneys.

UNITED STATES PATENT OFFICE.

FRANK H. MOONEY, OF CHICAGO, ILLINOIS.

GOLF BAG.

Application filed May 2, 1927. Serial No. 188,185.

My invention relates to improvements in golf bags and has for one object to provide a new and improved golf bag wherein automatic means are provided to insure that the bag, when released by the user, will remain in upright position. Another object is to provide an automatic standard or support which automatically comes into operation, or moves into supporting position, when the operator loosens the handle or strap of the bag. Another object is the provision of a unitary connection between the support and both handle and strap. Another object is the provision of means for mounting and housing the support with a minimum occupation of space within the bag, and a minimum of interference with the insertion or withdrawal of the clubs. Other objects will appear from time to time in the course of the specification and claims.

I illustrate my invention in the accompanying drawings more or less diagrammatically, wherein—

Figure 1 is a vertical section illustrating the support in withdrawn position;

Figure 2 is a similar section with the support in operative position;

Figure 3 is a vertical section on an enlarged scale illustrating the handle connection;

Figure 4 is a detail;

Figure 5 is an enlarged section on the line 5—5 of Figure 3; and

Figure 6 is an enlarged section on the line 6—6 of Figure 2.

Like parts are indicated by like characters throughout the specification and drawings.

A is a golf bag of any suitable material, which may be closed at the bottom by a relatively rigid cap A¹ of any suitable material. A² is any suitable rim for the upper end of the bag. A³ is a shoulder strap secured at one end to the upper end of the bag and at the other to an ear B⁴ upon the slide B, which will later be described in greater detail. A⁴ is any suitable handle also mounted upon the slide B. A⁵ indicates the usual golf ball pocket.

B is a slide member with which is associated the wire B¹ having an upper loop B², an intermediate loop B³ and a lower loop B⁴. The handle A⁴ is secured to the loops B² and B³, whereas the lower end of the strap A³ is secured to the loop B⁴. The loop

B⁴ continues inwardly and is provided at 55 its inner end with a roller or pulley B⁵, or its equivalent. The slide B, with the wire B¹, travels in the track B⁶ which is shown in cross section in Figure 5. The track may be formed of sheet metal with the closely 60 approached outwardly curled forward edges B⁷ which engage any suitable reinforcing or supporting member B⁸ suitably secured to the fabric of the bag A. B⁹ is a stop plate at the bottom of the track and B¹⁰ is 65 a stop and reinforcing plate at the top of the track B⁶.

Mounted in the bottom of the bag, upon the bottom member A¹ is a housing generally indicated as C, which includes a plurality of hollow radial fins C¹ outwardly bounded by upwardly and inwardly inclined walls C². It will be understood that whereas the walls C² incline or flare, the fins C¹ themselves are of substantially constant 70 thickness from top to bottom and that the intermediate connecting portions C³ are constantly spaced from top to bottom of the housing. The opposed inwardly arcuate wall portions C⁴ serve as a track or guide 75 for a vertically movable member D to which is secured any suitable flexible member D¹, which may be a chain or cord, and which extends upwardly through an aperture D² in the bag A to and about the pulley B⁵ and 80 downwardly through the aperture D², to be dead-ended as at D³ in the wall of the bag A or the pocket A⁵. D⁴ is a flexible member, for example a section of rubber hose, which is secured to the top of the housing C. 85

Within the housing, and within each of the fins C¹ is a supporting leg E the upper end of which is pivoted to the member D as at E¹. The member D, as shown in Figure 6, is illustrated as having vertically channeled radial flanges D⁵, within the channels of which the legs E are pivoted. The lower ends of the legs E are slidably positioned in the slots E² in the bottom plate A¹.

G indicates a latch pivoted as at G¹ to the 100 track member B⁶, as by the bolt G².

It will be realized that whereas I have described and shown a practical and operative device nevertheless many changes might be made in the size, shape, number 105 and disposition of parts without departing from the spirit of my invention. I therefore wish my drawings to be taken as in a

broad sense illustrative and diagrammatic rather than as limiting me to my specific disclosure.

The use and operation of my invention 5 are as follows:

My golf bag is primarily intended for use by players who do not wish to have caddies to carry their bags. The prime purpose of my invention is to avoid the necessity of laying the bag down, to render the use of a golf bag easier, and to insure that the clubs shall be held in position for removal from and insertion into the bag.

The user may carry the bag by means of 15 the strap A³ or the handle A⁴. Strap and handle being situated at the upper end of the bag, and above the center of gravity, the rear of the bag will depend below the point of support and the slide B will thus, 20 during normal carrying of the bag, always be positioned at the upper end of the track B⁶. When in such position, whether the bag is carried by the handle or by the strap, the roller B⁵ will draw out upon the flexible 25 member D¹ and will draw the member D to the top of the housing C, thus withdrawing the legs E within such housing, as shown in Figure 1. When the user wishes to put the bag down, assuming that the bag is 30 being lifted or carried by the right hand, he will take the upper edge of the bag with the other hand and release the strap or handle. The slide B will then drop into the lower position in which it is shown in 35 Figures 2 and 3, the pulley B⁵ will of course be lowered with the slide and the pressure on the flexible member will be sufficiently slackened to permit the member D to slide 40 down along the opposed walls C³. The legs E, pivoted to it, are thrust outwardly 45 through the slots E² in the bottom plate A¹, into the position shown in Figure 3 and the bag is supported by the tripod so formed. Whereas I have described and shown three 50 such feet, it will be realized that a greater number could be employed and I do not wish to be limited to any specific number.

The flexible member D⁴ has for purpose 55 to prevent cutting or nicking of the golf club handles when they are dropped into the bag. The housing C, except for its upper tip, is so inclined to the clubs as to prevent any possibility of damage, and the upper tip, which might otherwise scar or damage the clubs, is rendered perfectly harmless by the flexible member D⁴.

I claim:

1. The combination with a golf bag and carrying means therefor, of a ground engaging support at the lower end thereof, said support including a vertically movable member and a guide therefor, and a plurality of legs pivoted to said vertical member, the bag being apertured to permit the 60 projection of said legs, a flexible element se-

cured to said vertical member, and a connection between said flexible element and the carrying means, whereby the support is automatically moved to inoperative position when the carrying means is in use. 70

2. The combination with a golf bag of a carrying means therefor including a sliding member and a handle thereupon, a ground engaging support at the lower end of the bag including a plurality of legs adapted to be held in withdrawn position during the carrying of the bag, and a flexible connection between said legs and said sliding member. 75

3. The combination with a golf bag of a carrying means therefor including a sliding member and a handle thereupon, a ground engaging support at the lower end of the bag including a plurality of legs adapted to be held in withdrawn position during the carrying of the bag, and a flexible connecting member interposed between said legs and said sliding member, one end of said flexible member being dead-ended in the bag, the 80 85 90 95

slidable member including a pulley member about which the flexible member passes. 4. The combination with a golf bag of a carrying means therefor including a sliding member and a handle thereupon, a ground engaging support at the lower end of the bag including a plurality of legs adapted to be held in withdrawn position during the carrying of the bag, and a flexible connection between said legs and said sliding member, and a carrying strap, one end of which is secured to the upper portion of the bag and the other end of which is secured to said sliding member. 100

5. The combination with a golf bag of a carrying means therefor including a sliding member and a handle thereupon, a ground engaging support at the lower end of the bag including a plurality of legs adapted to be held in withdrawn position during the carrying of the bag, and a flexible connection between said legs and said sliding member, and means for holding said sliding member fixed at a predetermined point along its 105 110 115 normal path of excursion.

6. The combination with a golf bag of a ground engaging support at the lower end thereof, and a housing therefor, positioned within the bag, said housing including a central guide portion and a plurality of radial lateral extensions therefrom, said support including a member adapted to be guided by said central guiding portion for a movement on an axis generally parallel with the axis of the bag, and a plurality of legs pivoted thereto and positioned within the radial projections from the housing, the bag being apertured adjacent the lower ends of said radial projections for the passage of said legs. 120 125

7. The combination with a golf bag of a ground engaging support at the lower end 130

thereof, said support including a movable member positioned within the bag and means for guiding it along an axis generally parallel with the axis of the bag, and a plurality of legs pivoted thereto, and normally enclosed within the bag, the bag being apertured adjacent its lower end to permit the passage of said legs, said legs being slidably mounted in relation to the lower portion of the bag through which they pass.

8. The combination with a golf bag of a ground engaging support at the lower end thereof, and a housing therefor, positioned within the bag, said housing including a central guide portion and a plurality of radial lateral extensions therefrom, said support including a member adapted to be guided by said central guiding portion for movement on an axis generally parallel with the axis of the bag, and a plurality of legs pivoted thereto and positioned within the radial projections from the housing, the bag being apertured adjacent the lower ends of said radial projections for the passage of said legs, and a yielding protective member, adjacent the upper portion of said housing, adapted

to cushion the impact of clubs against the top of said housing.

9. The combination with a golf bag of a ground engaging support at the lower end thereof, and a housing therefor, positioned within the bag, said housing including a central guide portion and a plurality of radial lateral extensions therefrom, said support including a member adapted to be guided by said central guiding portion for movement on an axis generally parallel with the axis of the bag, a plurality of legs pivoted thereto and positioned within the radial projections from the housings, the bag being apertured adjacent the lower ends of said radial projections for the passage of said legs, a yielding protective member, adjacent the upper portion of said housing, adapted to cushion the impact of clubs against the top of said housing, and a flexible actuating element for said guided member, the yielding member being apertured to permit its passage therethrough.

Signed at Chicago county of Cook and State of Illinois, this 27th day of April, 1927.

FRANK H. MOONEY.
